FRICTION DRAFT GEAR

Albert F. Stuebing, Scarsdale, N. Y.

Application June 17, 1930. Serial No. 461,745

14 Claims. (Cl. 213—32)

My invention relates to friction draft gears for railway cars and it has for one of its objects the provision of improved means for facilitating the release of the friction elements of the gear.

5 Another object of the invention is to provide an improved form of housing for the gear especially adapted to withstand the bursting stresses to which it is subjected.

A primary feature of the invention is to provide 10 the draft gear with a plurality of friction elements, the frictional resistance of one of said elements being greater than the friction resistance of the other.

Another feature of the invention is to provide 15 the gear with a load-sustaining member having a plurality of friction surfaces of unlike contour.

A further feature of the invention consists in providing the draft gear with a pair of friction elements disposed on opposite sides of the longitudinal axis of the gear, said elements having opposed friction surfaces and one friction surface of one of the elements being of different contour than the corresponding friction surface of the other of the elements.

25 A still further feature of the invention consists in forming the walls of the gear housing which oppose the lateral forces exerted by the friction elements, with a plurality of laterally projecting portions extending transversely of the longitudinal axis of the gear.

A still further feature of the invention consists in integrally forming the walls of the draft gear housing with plate like portions spaced laterally therefrom.

35 Other and more specific features of the invention residing in advantageous forms, combinations and relations of parts will hereinafter appear and be pointed out in the claims.

In the drawings illustrating a preferred embodiment of the invention:

Figure 1 is a view, partly in section and partly in plan of the draft gear.

Figure 2 is a view, partly in elevation and partly in section, of the gear taken at right angles to the view illustrated in Figure 1.

Figure 3 is an end view of the gear taken on line 3—3 of Figure 1.

Figures 4, 5 and 6 are views taken on lines 4—4, 50 5—5 and 6—6 of Figure 1, respectively.

Figure 7 is a side elevational view of the central wedge member.

Figure 8 is an end elevational view of the wedge member.

55 Figure 9 is a side elevational view of the wedge

member as seen from the right hand side of Figure 7.

Figure 10 is an inside side elevational view of one of the friction elements.

Figure 11 is a sectional view taken on line 60 11—11 of Figure 10.

Figure 12 is an end view of the friction element of Figure 10 as viewed from the right hand side of that figure.

Figure 13 is an inside side elevational view of 65 another one of the frictional elements.

Figure 14 is a sectional view taken on line 14—14 of Figure 13.

Figure 15 is an end elevational view of the friction element of Figure 13 as viewed from the 70 right hand side of that figure.

Referring more particularly to the drawings 1 indicates the draft gear housing which is adapted to be mounted in a yoke, diagrammatically illustrated at 2. The housing is preferably closed 75 at its inner end by a wall 3 and is formed with top and bottom walls 4 and 5, respectively, and with side walls 6 and 7, respectively. To prevent the housing from moving inwardly, with respect to the car, its inner end may advantageously be 80 formed with laterally extending projections 8 adapted to cooperate with suitable stops (not shown).

Disposed within the forward portion 9 of the housing are the relatively movable friction elements comprising a central wedge 10 and a pair of shoes 11 and 12, respectively. The central member 10 is formed with opposed friction surfaces 13 and 14 respectively disposed in substantially vertical planes forming equal angles with 90 the longitudinal axis of the gear.

The shoe 11 is formed with opposed inner and outer frictional surfaces 15 and 16, respectively. The inner surface 15 is adapted to be disposed in a plane substantially parallel with the adjacent frictional surface 13 of the wedge member for cooperating therewith. The outer frictional surface 16 of the shoe is a plane surface and is adapted to be disposed in a substantially vertical plane for cooperating with a correspondingly disposed frictional surface 17 formed on the interior of the adjacent wall 6 of the housing. The friction surfaces 15 and 16 which are disposed in planes forming an acute angle with each other are formed on plate-like portions 18 105 and 19. At their outer ends these plate-like portions intersect and continue as an outwardly extending lip or lug 20 normally disposed in spaced overlapping relation to the adjacent side of the wedge member 10. The plate-like por- 110

tions 18 and 19 are connected by end walls 21 and by an intermediate web portion 22. The inner end of the plate-like portion 18 is formed with an inwardly extending portion 23, while the 5 inner end of the plate portion 19 is formed with an inwardly extending portion 24. The ends of the portions 23 and 24 are connected by a curved wall or plate portion 25 disposed in spaced relation to the plate portion 19 and end walls 21.

10 The other shoe 12 is likewise formed with opposed inner and outer frictional surfaces 26 and 27. The inner friction surface 26 is disposed in a plane substantially parallel with the frictional surface 14 of the central wedge member 15 for cooperating therewith. The outer frictional surface 27, however, instead of being a plane surface as is the outer frictional surface 16 of the shoe 11 may be and preferably is formed as a curved substantially cylindrical surface and is 20 adapted to cooperate with a similarly formed friction surface 28 on the interior of the portion 9 of the housing. Since the shoe 12 is of the same construction as the shoe 11, with the exception of the contour of its outer frictional 25 surface, corresponding parts of the two shoes are designated by similar reference numerals. It should, of course, be noted that the plate portion 19 of the shoe 12, upon which the friction surface 27 is formed, is curved and the outwardly 30 projecting lip or lug 20 is, therefore, correspondingly curved as is the portion of the wedge member which it overlaps.

To return the friction elements to the positions illustrated in Figures 1 and 2, after they 35 have been actuated by either buffing or draft forces, a plurality of springs 29 and 30 may be employed. The spring 29 may conveniently engage the rear or inner wall 3 of the housing and the inwardly projecting portions 24 of both of 40 the friction shoes while the spring 30 may bear against a boss 31 projecting inwardly from the rear wall 3 and the portions 23 of both shoes. The friction elements may advantageously be retained in assembled position by a longitudinally 45 extending bolt 32. The head of the bolt is preferably disposed within the boss 31 and engages an annular portion 33 formed integrally with the latter. The removable nut 34 of the bolt is preferably disposed within a suitably formed 50 recess 35 in the central wedge member. In this manner it will be perceived that the draft gear may be quickly and easily assembled and shipped as a unit.

In the operation of the gear the central wedge 55 member is actuated by a follower diagrammatically illustrated at 36. As is illustrated if the gear is operated by buffing forces the follower 36 is moved inwardly by a coupler (not shown), the housing being held stationary in the manner 60 heretofore described, while if the gear is operated by draft forces the housing moves toward the follower, the latter being held stationary by suitable stops (not shown). In either event the force supplied to the wedge is transmitted 65 to the friction shoes through the cooperating wedging surfaces setting up lateral forces which press the shoes against the friction surfaces of the housing and also setting up forces tending to move the shoes inwardly relatively to the latter. The inward movement of the shoes is resisted by the springs 29 and 30 and by the friction forces between the shoes and the housing. The cooperating friction surfaces of the shoes and housing converge or taper inwardly so that 70 the distance between the shoes decreases as they

are moved inwardly thereby causing relative movement between the wedge member and shoes, and further increasing the frictional force between the various elements of the gear. Although the wedge exerts equal forces on the shoes 11 and 12, the forces acting between the housing and the shoe 11, provided with the plane friction surface 16, directly oppose and act in planes parallel to the lateral components of the forces exerted by the wedge on shoe 11 while the forces acting between the housing and the shoe 12, provided with the cylindrical friction surface 27, act toward the axis of the curved surface. The resultant of all of the forces acting between the housing and the shoe 12, with the exception of the ones acting through the horizontal center line of the cylindrical surface thereof, are, therefore, disposed at an angle to the lateral components of the forces transmitted from the wedge to the shoe and consequently are of greater magnitude than the last named forces. Thus, it will be appreciated that since the total pressure between the wedge and shoe 11 is equal to the total pressure between the housing and shoe 11 and the pressure between the wedge and shoe 12 100 is the same as that between the wedge and shoe 11 but is less than the pressure between the housing and shoe 12, the total pressure and therefore the frictional resistance between the cylindrical surfaces of the shoe 12 and the housing 105 will be greater than the total pressure and frictional resistance between plane surfaces of the shoe 11 and the housing thereby causing a differential frictional resistance. With the parts of the gear in normal position the springs 29 and 30 110 will deliver an equal pressure to the friction shoes. During the closure of the gear and due to the difference in frictional resistance between the flat face shoe and the housing and the cylindrical shoe and the housing, the flat face shoe will tend 115 to move at a greater rate of speed than the cylindrical shoe. This tendency of the flat face shoe to move at a greater rate of speed and therefore a greater distance than the cylindrical shoe will be to some extent counteracted by the springs 120 since the latter will exert a greater resistance to the shoe moving the greater distance. In the particular embodiment illustrated, this difference in frictional resistance between the shoes is, however, of no importance during closure of 125 the gear but is only advantageous to facilitate release of the gear to enable the friction elements to quickly return to their normal positions. From the foregoing analysis of the force 130 reactions between the shoes 11 and 12 and the housing it will be perceived that the shoe 12 offers greater resistance to outward movement relatively to the housing than the shoe 11. Consequently the springs 29 and 30 exert a greater force on the shoe 11 than on the shoe 12 thereby 135 moving the former outwardly and releasing the pressure between the wedge and shoe 12. Thus the release of the gear is greatly facilitated.

Due to the cylindrically cooperating faces of the shoe 12 and the housing the shoe is adapted 140 to rotate about the axis of its cylindrical surface so as to compensate for deviation from parallelism of any of the plane surfaces of the gear. This, of course, results in an equal distribution of the forces on all of the friction elements and the 145 housing.

In draft gear housings having opposed friction surfaces the walls connecting the portions of the housing on which the friction surfaces are formed are in tension and it is in these walls that 150

- forces are set up opposing the lateral forces exerted by the gear elements. Since the opposing forces, however, do not act in the same planes as the lateral forces it will, of course, be appreciated that the sides of the housing on which the friction surfaces are formed are subjected to bending moments. In the form of housing illustrated in the drawings it will be perceived that the top and bottom walls 4 and 5, respectively, are in tension while the side walls 6 and 7 are the ones subjected to bending moments. In order to prevent bending of the side walls 6 and 7 the portion 9 of these walls is formed with a greater amount of metal than are the top and bottom walls 4 and 5 of this portion of the housing. Although this extra metal may be arranged in a variety of ways it is preferred to dispose it in the manner illustrated in the drawings. Thus the walls 6 and 7 are each formed with a plurality of laterally projecting portions 37 extending transversely of the longitudinal axis of the gear. At their outer ends these portions are integrally connected by plate-like portions 38 spaced laterally of the adjoining walls of the housing and preferably disposed in substantially vertical planes. The hollow box shape reinforcements thus formed greatly increase the strength of the side walls without materially increasing the weight of the casting and by maintaining a substantial uniformity of cross section the danger of shrinkage cracks and like defects in the casting operation is avoided.
- I claim:
1. A draft gear for railway cars involving a load sustaining column member, movable elements respectively having friction surfaces in engagement with the column member, wedging means for actuating said elements, and spring means opposing movement of said elements, said elements having wedging faces inclined in the same direction with respect to the longitudinal axis of the gear for cooperating with said means, the contours of the friction surfaces of said elements and the inclination of said wedging faces being such that the summation of the friction producing forces between the column member and one of said friction surfaces is greater than the summation of the friction producing forces between the column member and another of said surfaces. 110
  2. A draft gear for railway cars involving a load sustaining column member, movable elements respectively having friction surfaces in engagement with the column member, wedging means for actuating said elements, and spring means for opposing movement of said elements, said elements having wedging faces inclined in the same direction with respect to the longitudinal axis of the gear for cooperating with said wedging means, the engaging friction surfaces of one of said elements and the housing being curved and having greater surface contact transversely of the longitudinal axis of the gear than the engaging friction surfaces of another of said elements and the housing so as to produce a greater friction force between the first mentioned sets of engaging friction surfaces than between the second mentioned sets of engaging friction surfaces. 120
  3. A draft gear for railway cars involving a housing provided with two friction surfaces, elements movable relatively to said housing and respectively having wedging faces inclined in the same direction with respect to the longitudinal axis of the gear, spring means opposing move- 130
  - ment of said elements, and wedging means for actuating said friction elements having faces respectively in engagement with the wedging faces of the latter, said elements respectively having friction surfaces in engagement with the surfaces of the housing, the engaging friction surfaces of one of the elements and housing being of such different contour from the engaging friction surfaces of the other element and housing as to produce a greater friction force between one of the sets of said engaging friction surfaces than between the other of the sets of friction surfaces, and the inclination of said wedging faces being such as to maintain the difference in friction forces between said sets of friction surfaces. 140
  4. A draft gear for railway cars involving a load sustaining column member, elements movable relatively to the column member and respectively having friction surfaces in engagement with the latter, spring means opposing movement of said elements, and wedging means having faces inclined in the same direction with respect to the longitudinal axis of the gear for cooperating with said elements, the friction surface of one of said elements having a curved portion and the friction surface of another of said elements having a plane portion, said friction surfaces being so arranged and the inclination of the wedging faces being such that the summation of the friction producing forces between one of said elements and the column member is greater than the summation of the friction producing forces between another of said elements and the column member. 150
  5. A draft gear for railway cars involving a load sustaining column member having two friction surfaces, one of said surfaces being plane and the other of said surfaces being curved, wedging means, movable friction elements, and spring means opposing movement of said elements, said elements being movable relatively to the column member and respectively provided with faces inclined in the same direction with respect to the longitudinal axis of the gear for cooperating with said wedging means, said elements also respectively having surfaces in engagement with said plane and curved friction surfaces of the column member, said friction surfaces being so arranged and the inclination of the wedging faces being such that the summation of the friction producing forces between the said column member and the element in engagement with said curved surface is greater than the summation of the friction producing forces between the column member and the element in engagement with said plane surface. 160
  6. A draft gear for railway cars involving a housing, friction elements disposed within the housing and movable relatively thereto, a wedging member interposed between the friction elements, and spring means opposing movement of said elements, said elements respectively having faces inclined in the same direction with respect to the longitudinal axis of the gear for cooperating with said wedging member, one of said friction elements having a curved surface in engagement with the housing and the other of said elements having a substantially plane surface in engagement with the housing, said friction surfaces being so arranged and the inclination of the wedging faces being such that the summation of the friction producing forces between the first named element and housing is greater than the 170

summation of the friction producing forces between the last named element and housing.

7. A draft gear for railway cars involving a housing, a movable central wedge member disposed within the housing and having wedging faces respectively forming equal angles with the axis of movement of the wedge, movable friction elements operatively interposed between the wedge and housing and having surfaces in frictional engagement with the latter, and spring means opposing movement of said elements, said elements also respectively having faces inclined in the same direction with respect to the axis of movement of the wedge for cooperating with the faces of said wedge, the friction surface of one of said elements being of such different contour from the friction surface of another of said elements that the summation of the friction producing forces between one of the elements and the housing is greater than the summation of the friction producing forces between another of the elements and the housing.

8. A draft gear for railway cars involving a housing having friction surfaces, a central wedge member movable within said housing, two movable friction elements arranged on opposite sides of the wedge member, and spring means opposing movement of said elements, said elements respectively having wedging surfaces and friction surfaces, said friction surfaces being in engagement with the friction surfaces of the housing and said wedging surfaces being inclined in the same direction with respect to the longitudinal axis of the gear and being in engagement with said wedging member, the engaging friction surfaces of one of said elements and housing being of such different contour from the engaging friction surfaces of the other of said elements and housing as to produce a greater friction force between one of the sets of engaging friction surfaces than between the other of the said sets of friction surfaces, and the inclination of the wedging surfaces being such as to maintain the difference in friction force between said sets of friction surfaces.

9. A draft gear for railway cars involving a housing, a central wedge member movable within said housing, a pair of movable friction elements respectively having faces inclined in the same direction with respect to the longitudinal axis of the gear in engagement with said wedge member, and spring means opposing movement of said elements, one of the elements of said pair being disposed on one side of the wedge member and the other element thereof being disposed on the opposite side, each of said elements having a friction surface in engagement with the housing, the friction surface of one of the elements being a substantially plane surface and the friction surface of the other of the elements being a curved surface, said friction surfaces being so arranged and the inclination of the wedging faces being such that the summation of the friction producing forces between the last-named element and the housing is greater than the summation of the friction producing forces between the second-named element and the housing.

10. A draft gear for railway cars involving a load sustaining column member having friction surfaces, wedging means having inwardly converging surfaces, movable friction elements respectively interposed between the column member and the wedging means, and spring means opposing movement of said elements, each of said elements having surfaces respectively in engage-

ment with the surfaces of said column member and said wedging means, said wedging means being adapted to exert equal pressures on said elements and the cooperating surfaces of one of said elements and the column member being such different contour from the cooperating surfaces of another of said elements and the column member that the summation of the friction producing forces between one of said elements and the column member is greater than the summation of the friction producing forces between another of said elements and the column member.

11. A draft gear for railway cars involving a housing having friction surfaces, wedging means having opposed inwardly converging wedging faces forming equal angles with the longitudinal axis of the gear, a plurality of movable friction elements operatively interposed between the housing and wedging means, and means for opposing movement of said elements, each of said elements having a friction surface in engagement with one of said surfaces of the housing and a wedging surface in engagement with the wedging means, the engaging friction surfaces of one of said elements and housing being so formed with respect to the engaging friction surfaces of another of said elements and housing as to produce a greater friction force between one of the sets of said engaging friction surfaces than between another of said sets of friction surfaces.

12. A draft gear for railway cars involving a housing having friction surfaces, wedging means having surfaces inclined in the same direction with respect to the longitudinal axis of the gear, friction elements respectively interposed between the housing and the wedging means, and spring means opposing movement of said elements, each of said elements having surfaces respectively in engagement with the surfaces of said housing and said wedging means, said wedging means being adapted to exert equal pressures on said elements and the cooperating surfaces of one of said elements and the housing being of such different contour from the cooperating surfaces of another of said elements and the housing that one of said elements exerts greater pressure on said column member than the other of said elements.

13. A draft gear for railway cars involving a load sustaining column member, movable elements respectively having friction surfaces in engagement with the column member, wedging means having surfaces inclined in the same direction with respect to the longitudinal axis of the gear respectively cooperable with said elements for actuating the latter, and spring means opposing movement of said elements, the friction surfaces of said elements being so formed that the ratio of the lateral component of the wedging force acting on one of said elements to the frictional force acting between that element and the column member is greater than the ratio of the lateral component of the wedging force acting on another of said elements to the frictional force acting between the latter element and the column member.

14. A draft gear for railway cars involving a load sustaining column member having friction surfaces, movable elements having friction surfaces respectively cooperable with said surfaces of the column member, said elements having wedging faces inclined in the same direction with respect to the longitudinal axis of the gear, wedging means having faces respectively cooperable with the wedging faces of the elements for actuating said elements, and spring means opposing

movement of said elements, the cooperating friction surfaces of one of said elements and column member being so formed with respect to the cooperating friction surfaces of another of said elements and column member as to produce a greater friction force between one of the sets of said cooperating friction surfaces than be-
 tween another of said sets, and the inclination of the wedging faces of the elements and the wedging means being such that the elements co-operate with the latter to maintain the difference in friction forces between said sets of cooperating friction surfaces. 80
